[57] CLAIM

The ornamental design for a electronic game housing, as shown and described.

DESCRIPTION

- FIG. 1 is a perspective view of a electronic game showing our new design;
 FIG. 2 is a front elevational view thereof;
 FIG. 3 is a right side elevational view thereof;
 FIG. 4 is a rear elevational view thereof;
 FIG. 5 is a top plan view thereof;
 FIG. 6 is a bottom plan view thereof; and,
 FIG. 7 is a left side elevational view thereof.
